UNITED STATES PATENT OFFICE.

EUGENE CURRAN, OF CARDIFF, AND JOHN JOSEPH HICKEY, OF LLANISHEN, NEAR CARDIFF, WALES.

VEHICLE.

Application filed September 4, 1925, Serial No. 54,569, and in Great Britain June 30, 1925.

This invention relates to vehicles of the kind in which the floor comprises or includes one or more hinged flaps so that the bottom is divided generally into two halves about 5 a longitudinal central line and the two halves can be arranged either symmetrically and extending upwards to the sides from the middle or in line, so as to extend obliquely across the truck in which latter position the 10 contents may be automatically discharged.

The invention has for its object to provide improved means whereby the movable flap or flaps may be supported in raised position when the truck is loaded and during 15 transportation.

A further object of the invention is to provide an improved arrangement whereby the movable flaps may be supported intermediate their extreme positions.

20 The invention is illustrated in the accompanying drawing which shows a railway wagon of which the floor comprises six hinged flaps pivoted about a central rod and arranged three on each side.

25 Fig. 1 shows a side view, modified as follows.

In the left hand panel, the flap nearer the observer is broken away, in the centre panel, the supports or struts for the nearer flap are 30 not illustrated, and in the right-hand panel the counterweight for the further flap is dotted for the sake of clearness.

Fig. 2 is a sectional end elevation of Fig. 1 showing the truck in loading condition.

35 Fig. 3 is an end elevation showing the truck in the discharging position.

Fig. 4 illustrates a modification in end sectional elevation, and Fig. 5 shows a further improvement applicable to any of the previous forms.

40 Referring now to the drawing, the end frame of the truck is shown of ordinary construction and the body comprises two closed ends and two sides having three openings 1 positioned below an upper vertical wall 2. The floor of the truck comprises three pairs of hinged flaps, 3, 4 pivoted to a longitudinal bar 5 supported in blocks 6 carried by a longitudinal beam 7. The flaps 3 (nearer in Fig. 1) are supported by T-iron 45 straps 8 secured to the hinge knuckles 9, and the flaps 4 by straps 10 secured to knuckles 11. To each of the hinged flaps 3 are secured a pair of straps 12 supporting a counter- 50 weight 13 (Fig. 2) which normally keeps the

flap in the raised position, and the flaps 4 are provided with a pair of straps 14 supporting a counterweight 15. The free ends of the flaps are adapted to be supported by struts 16 hinged adjacent to the free ends of the flaps and provided at their lower ends with rollers 17 adapted to run on transverse braces, the lower ends of the struts being adapted to be drawn inwardly for the purpose of releasing the flaps by means of one or more connecting rods 18 adapted to be moved transversely by means of a hinged handle 19. Obviously the connecting rods may be threaded and operated by means of a crank if desired. In the erected position 60 of the struts, the rollers 17 abut against sheaves or sockets 20 and are prevented from inward movement by means of cross pins 21 passing through the walls of the sockets. Preferably, the three supporting struts of 70 each side are connected by a cross brace 22 as shown in Fig. 1.

Catches of any suitable or known form are provided for securing the edges of the flaps to the lower edge of the side wall 2. 80 In practice, I prefer the known form of catch in which a hook 23 carried by the flap is passed upwardly through a hole in a horizontal bracket 24 mounted on the wall 2 and is thereafter held in the raised position by a notched sliding bar 25 of which the notch is adapted to be moved away from the position in which it registers with the lip of the hook.

85 It will be realized from the description already given that the flaps normally assume the upwardly-inclined position illustrated in Fig. 2, and that when the catches are engaged and the struts are firmly secured in the vertical position by the means described 90 the truck is ready for loading. For discharge, all that is necessary is to release the catches and pull away the lower ends of the struts 16 at one side of the truck, whereupon the flaps of that side will fall down under 95 the weight of the load to the position illustrated by 3 in Fig. 3, and the contents of the truck will be discharged under gravity sliding over the inclined bottom.

100 It should here be mentioned that owing to the removal of a considerable portion of the usual side wall of the truck the ends of the truck and the supports of the side pieces 2 require considerable strengthening.

105 Although the invention as hitherto de-

110

scribed has included three pairs of flaps to each side of the truck it will be realized that two pairs or one pair only may be employed where found desirable. As a rule, 5 where more than one pair is used, the truck may be divided by partitions such as that indicated at 30 in Figs. 2 and 3 into compartments so that the load discharged by lowering one flap may approximate to the load 10 capable of being carried by a road vehicle. Such partitions serve to strengthen the construction of the truck. Where, however, such partitions are not employed, preferably the stanchions 26 between the openings 1 will 15 be strengthened by means of gussets 27, Fig. 4, extending into the interior of the truck. The ends may be strengthened by providing L-shaped straps of angle or T-iron the vertical lengths of which are bolted 20 to said ends, the horizontal lengths being bolted to the longitudinal braces of the under-frame.

In Fig. 4 we illustrate a modification in 25 which the counterweights are dispensed with and the flaps are urged in the raised position by means of springs. Further, the supporting struts 16 are arranged to run on supports 29 extending longitudinally of the truck in case this should be more convenient, any suitable means for holding them 30 in the erect position, and releasing them therefrom in case of need being employed.

Fig. 5 illustrates the provision of two additional half doors 27, 28 hinged respectively 35 to the lower edge of the wall 2 and to the under-frame of the truck. When the truck is discharging or transporting heavy material, the half door 27 is folded up behind the wall 2 and the half door 28 may be 40 folded beneath the flap and lie on the under-frame of the truck, or in case of discharging may be extended to lie on a hinged support 33 as indicated on the right hand side of Fig. 5. When the truck is transporting 45 lighter material, however, both flaps may be held in horizontal position as indicated by the flap 3 in Fig. 5, in which case the half doors 27, 28 are arranged vertically as shown on the left hand side of Fig. 5 to 50 close the opening in the side wall. Preferably, the half doors are provided with projecting lugs which pass through slots in the flap 3 and are thereafter held in place by cotter pins. By this means the carrying 55 capacity of the truck can be substantially increased when a load of lighter material requires to be transported.

For use in this manner, any suitable means 60 may be employed for supporting the lower ends of the struts 16 to accommodate the intermediate position of the flap 4, and suitable brackets 31 are provided on the stanchions 26 having lugs which may be rotated beneath the ends of the flaps 3 and 4 and 65 provided with suitable fastening means to

support it in the intermediate position. Further brackets 32 may be provided below the brackets 31 for raising the discharging level where found desirable.

It is to be understood that the term "half doors" does not mean that the two half doors are of equal width, as the upper half-door may be of any depth agreeing with the desired additional amount of capacity and consequent position of the catches on the framing whereby the flap is to be held in an intermediate position. 70 75

Obviously, in all cases, the flaps overlie the framing or adjacent flaps so that the bottom of the truck is properly closed. 80

The invention includes the modification in which one of the half floors is permanently fixed in the raised position, the other half floor being tiltable, and adapted to be arranged either symmetrically or in line with the fixed half, which modification may be cheaper to construct and satisfy requirements in the case of small gauge trucks working for example between a quarry and a wharf where the discharge is only required to take place from one side. 85 90

We claim:

1. In a vehicle, a frame, a bottom formed in two parts, said parts constituting the full area of the bottom transversely of the vehicle, one part sloping down from the side of the vehicle to the middle, and the other part being hinged relatively to the first mentioned part, said hinged part being adapted to be held symmetrically with or in line with 95 said first mentioned part, and a strut pivotally mounted to the free edge of the hinged member and adapted to rest on said frame to support said part in the symmetrical position. 100 105

2. In a vehicle, a frame, a bottom formed in two parts hinged together longitudinally of the truck, said parts constituting the full width of the bottom transversely of the vehicle, said hinged parts being adapted to be held symmetrically with or in line with each other, and a strut pivotally mounted to the free edge of each part and adapted to rest on said frame to support said part in the raised position. 110 115

3. In a vehicle, a body having side walls, an underframe, an opening in a side wall, a bottom including an outwardly-directed flap hinged centrally of the vehicle, said flap constituting the full width of the bottom from the central hinge to the side wall, the free end of said flap being adapted to extend through said opening and the hinge of the flap being intermediate the height of said opening, means to support said flap at the top of said opening, comprising a strut hinged to said flap adjacent its free edge and adapted to stand up vertically on said under-frame. 120 125

4. In a vehicle, a body having side walls, 130

an underframe, an opening in a side wall, a bottom including an outwardly-directed flap hinged centrally of the vehicle, the free end of said flap being adapted to extend through said opening, and the hinge of the flap being intermediate the height of said opening, means to engage said flap at the top of said opening, means to support said flap at the bottom of said opening, a strut hinged to the under face of said flap near its free edge, a roller mounted in the bottom of said strut, and a horizontal member in said underframe to support said roller.

5. In a vehicle, a body having side walls, an underframe, an opening in a side wall, a bottom including an outwardly-directed flap hinged centrally of the vehicle, the free end of said flap being adapted to extend through said opening, and the hinge of the flap being intermediate the height of said opening, means to engage said flap at the top of said opening, means to support said flap at the bottom of said opening, a strut hinged to the under face of said flap near its free edge, a roller mounted in the bottom of said strut, and a transverse race in said underframe to support said roller.

6. In a vehicle, a body having side walls, an underframe, an opening in a side wall, a bottom including an outwardly-directed flap hinged centrally of the vehicle, the free end of said flap being adapted to extend through said opening and the hinge of the flap being intermediate the height of said opening, means to engage said flap at the top of said opening, means to support said flap at the bottom of said opening, a strut hinged to the under face of said flap near its free edge, a roller mounted in the bottom of said strut, a horizontal member in said underframe to support said roller, and means to lock said roller on said horizontal member when said strut is approximately vertical.

7. In a vehicle, a body having side walls, an underframe, an opening in a side wall, a bottom including an outwardly-directed flap hinged centrally of the vehicle, the free end of said flap being adapted to extend through said opening and hinge of the flap being intermediate the height of said opening, means to engage said flap at the top of said opening, means to support said flap at the bottom of said opening, a strut hinged to the under face of said flap near its free edge, a roller mounted in the bottom of said strut, a transverse race in said underframe to support said roller, and means to lock said roller on said cross brace when said strut is approximately vertical.

8. In a vehicle, a bottom formed in two parts, one part sloping down from the side of the vehicle to the middle, the other of

said parts being hinged relatively to the first-mentioned part, means being provided whereby said hinged part may be held symmetrically with or in line with said first-mentioned part, and means to support said part in a position intermediate said positions.

9. In a vehicle, an underframe, a longitudinal rod supported centrally thereon, two outwardly-directed flaps hinged thereto and means whereby said hinged flaps may be held symmetrically with or in line with each other, and means to support said flaps in a position intermediate said positions.

10. In a vehicle, a body including side walls, an underframe, a transverse vertical partition dividing said body into compartments, a similar opening to each side wall of each compartment, a bottom to each compartment comprising outwardly-directed hinged flaps adapted to tilt in said openings, means to hold said flaps at the top of said openings, means to hold said flaps intermediate said openings, and half doors hinged at the top of said openings adapted to close the openings left by and above said flaps in said intermediate positions.

11. In a vehicle, a body including side walls, an underframe, a transverse vertical partition dividing said body into compartments, a similar opening to each side wall of each compartment, a bottom to each compartment comprising outwardly-directed hinged flaps adapted to tilt in said openings, means to hold said flaps at the top of said openings, means to hold said flaps intermediate said openings, half doors hinged at the top of said openings adapted to close the openings left by and above said flaps in said intermediate positions, and half doors hinged at the bottom of said openings adapted to close the openings left by and below said flaps in said intermediate positions.

12. In a vehicle, a body having side walls, an underframe, an opening in a side wall, a bottom including an outwardly-directed flap hinged centrally of the vehicle, the free end of said flap being adapted to extend through said opening, and the hinge of the flap being intermediate the height of said opening, means to engage said flap at the top of said opening, means to support said flap at the bottom of said opening, a half door pivoted to the bottom of said opening, means to support said flap at the bottom of said opening, and means to support said half door in line with said flap in said bottom position.

In testimony whereof we affix our signatures.

EUGENE CURRAN.
JOHN JOSEPH HICKEY.
